(57) **CLAIM**

The ornamental design for a hanging display fixture, as
shown and described.

DESCRIPTION

FIG. 1 is a perspective view of the hanging display fixture
showing my new design;

FIG. 2 is a front elevational view thereof;

FIG. 3 is a side elevational view thereof, the opposite side
being a mirror image thereof;

FIG. 4 is a top plan view thereof; and,

FIG. 5 is a bottom plan view thereof.
